[57] **CLAIM**

The ornamental design for a combined power and telephone wall plate, substantially as shown and described.

DESCRIPTION

FIG. 1 is a front and side perspective view of a combined power and telephone wall plate showing our new design;

FIG. 2 is a front elevational view thereof, the rear being unornamented;

FIG. 3 is a right side elevational view thereof, the left side being substantially identical thereto;

FIG. 4 is a bottom plan view thereof.

FIG. 1

FIG. 2

FIG. 3

FIG. 4
